UNITED STATES PATENT OFFICE.

WILLIAM H. ZORN, OF HARRISBURG, NEBRASKA.

DESIGN FOR A CLOTHES-PIN.

SPECIFICATION forming part of Design No. 32,970, dated July 17, 1900.

Application filed May 24, 1900. Serial No. 17,888. Term of patent 7 years.

To all whom it may concern:

Be it known that I, WILLIAM H. ZORN, a citizen of the United States, residing at Harrisburg, in the county of Banner and State of Nebraska, have produced a new and original Design for a Clothes-Pin, of which the following is a specification.

This invention relates to a new and original design for clothes-pins, and the essential feature resides in the formation of a circular spirally-coiled head with legs extending therefrom and crossing immediately thereunder and projecting laterally and returned inwardly in straight lines to form an intermediate diamond-shaped figure from the lower terminal of which the said legs are bowed outwardly in convex planes and converged at their lower ends, where eyes are formed.

In the drawings, Figure 1 is a perspective view of a clothes-pin embodying the features of the design. Fig. 2 is an edge elevation of the pin.

The numeral 1 designates a head composed

of spirally-arranged circular coils 2, from which upper leg-sections 3 extend inwardly 25 in straight lines, one across the other, and are then continued into outwardly-extending angular deflections in straight lines, as at 4, and returned in said lines toward the center to produce an intermediate diamond-shaped figure. From the lower termination of the said 30 figure the legs are formed with outwardly-bowed or convex portions 5 and converge at their lower terminals, where eyes 6 are formed.

Having thus described the invention, what 35 is claimed as new is—

The design for a clothes-pin, herein shown and described.

In testimony that I claim the foregoing as my own I have hereto affixed my signature in 40 the presence of two witnesses.

WILLIAM H. ZORN.
